UNITED STATES PATENT OFFICE.

SAMUEL M. JOSEPH, OF VINELAND, NEW JERSEY, ASSIGNOR TO JOSEPH BROTHERS,
OF VINELAND, NEW JERSEY.

COAT.

Original application filed June 3, 1925, Serial No. 34,639, Patent No. 1,599,018, dated September 7, 1926.
Divided and this application filed December 4, 1925. Serial No. 73,159.

The present invention relates to coats of that style commonly worn by men, and the subject matter has been divided from my application bearing Serial No. 34,639, filed 5 June 3, 1925, patented September 7, 1926, #1,599,018.

The object of the present invention is to improve upon coats by providing sleeves with reinforcing linings incorporated in the 10 sleeves in a novel manner to produce strength and durability and allow the sleeves of the coat to be manufactured at a comparatively low cost.

With the above and other objects in view 15 as will appear as the description proceeds, the invention resides in the details of construction as will be hereinafter more fully described and claimed.

In the drawing:—

20 Figure 1 is a perspective view of the coat embodying my invention.

Figure 2 is a transverse section through one of the sleeves, and

25 Figure 3 is a fragmentary plan view showing the inside of a portion of the coat.

Referring to the drawing in detail, it will be seen that the body of the coat, as shown in the present example, includes the back section 5, and the two side or front sections 30 6, which are faced at their edges in the usual manner as is indicated at 7 and 8. The sections 6 are attached to the edges of the section 5 by suitable seams 9. The sleeves 10 are attached to the body in the usual manner. Patch pockets 11 are sewed to the outer 35 surface of the sections 6, in the usual manner. Thus far it will be seen that the coat is more or less of conventional construction.

Referring now particularly to my improvements for reinforcing the coat, it will be seen that 13 represents two strips of rubberized material, which are applied to the inner surface of the sections 6 immediately under the arm pits. These strips 13 are applied by stitching extending adjacent its lower edge while its upper edge is folded and stitched in the seam of the respective 45 sleeve 10, as is indicated at 14.

A rubberized strip 15 is applied to the

inner surface of each section 6 so that its 50 longitudinal edges are disposed one above, and one below the upper end of the adjacent patch pockets 11, as is indicated to advantage in both Figures 1 and 3. This rubberized strip extends from the seam 9, to the stitching 55 at the inner edge of the facing 7, and the end at the seam 9 is folded and sewed with the hem, while the other end is sewed with the stitching 16 of the facing 7. Stitching 17 attach the longitudinal edges of each strip 60 to its respective sections 6.

With this coat it is preferable to use the well known sleeve lining which extends from the intermediate elbow portion of the sleeve down into the cuff 18 of each sleeve. This 65 lining, as is shown to advantage in Figure 2 extends circumferentially in the sleeve starting from the seam 19, being tucked into the seam 20, and finally stitched as at 21 so that the lining extends transversely over the 70 major portion of the inner side of the sleeve and about half way transversely of the outer portion of the sleeve.

It is thought that the construction, utility, and advantages of my improved and novel 75 reinforcing features will now be clearly understood without a more detailed description thereof.

It is apparent that numerous changes in the details of construction, in the sizes, in the 80 materials, and in the combination and arrangement of parts may be resorted to without departing from the spirit or scope of the invention as hereinafter claimed or sacrificing any of its advantages.

Having thus described the invention, what I claim as new:—

In a coat, a sleeve comprising an inner piece, an outer piece, said pieces being connected together by seams, a strip of reinforcing lining in said sleeve having one edge stitched in one seam and another edge stitched to the outside piece, and an intermediate portion stitched in the other seam.

In testimony whereof I affix my signature.

SAMUEL M. JOSEPH.
